ARTICLE OF FURNITURE

Clarence L. Dewey, Elkhart, Ind.

Application January 6, 1945, Serial No. 571,647

2 Claims. (Cl. 155—196)

1

The present invention relates to an article of furniture such as a chair, table, and the like which is equipped with legs for support of a seat or top of some kind. More particularly the present invention has to do with means for joining together the various components, and also certain preformed units, of the furniture article. By partly, but not completely, assembling the parts of the furniture article at the factory, it is possible with advantage to make a knock-down shipment and then let the dealer or user complete the assembly. It is an object, therefore, of my invention to devise a form of connections whereby the several parts of the furniture article may be finally assembled with a minimum of effort, and yet with assurance of security and dependability. The means for accomplishing this and other objects of my invention centers in a junction fitting of improved and unique construction—a fitting which, in use, is wholly concealed and which lends itself to bracing of and attachment to the adjacent parts in a manner whereby to provide a resulting structure that is exceedingly strong and rigid.

The herein disclosed furniture article, of which a suggestive embodiment is set forth in the accompanying drawings, is illustrated in the manner following:

Figure 1 shows in front elevation a conventional form of chair;

Fig. 2 is a side elevation of the chair;

Fig. 3 which is a horizontal section through the chair, taken on line 3—3 of Fig. 2, shows its two side units, completely assembled, as separated from the channel bars which are designed for interconnection thereof;

Fig. 4 is an enlarged detail in section, taken on line 4—4 of Fig. 2;

Fig. 5 is an enlarged detail in transverse section, taken on line 5—5 of Fig. 3;

Fig. 6 is a perspective view looking toward the interior of the junction fitting one of which is attached to each leg;

Fig. 7 which is a view in section taken on line 7—7 of Fig. 8 shows a modified connection for the channel bar to the junction fitting; and

Fig. 8 is an elevational view looking into the channel of the bar end when made according to Fig. 7.

The present furniture article, a chair, for ex-

ample, comprises two units, both alike, but right and left, so that a description of one will suffice for the other. Each unit comprises front and rear legs L, and a connecting rail R therebetween. The rail, as shown, is extended from the front leg at a point near its top to join with the rear leg at about the same elevation above which the latter is upwardly extended in the form of a support 10 for carrying, in conjunction with the other unit, a back 11 of any appropriate construction. Likewise a seat or top 12 which may be supported over each connecting rail of the two units is desirably extended therebetween in the final assembly of the furniture article.

15 The legs L may be of tubular metallic construction with appropriate configuration to meet esthetic requirements. As shown, each leg in the region where the connecting rail R is joined thereto is of generally rectangular cross-sectional form, adjacent faces being thereby provided. Desirably the corners between these faces are rounded as best shown in Fig. 4. To an inner (one or more) face of such a leg I affix a junction fitting J (see Fig. 6) desirably of metal which is

20 die formed, the fitting comprising an angular wall 15 from whose opposite ends are extended wings 16 and 17 in substantially right angular relation to each other. At opposite ends the wings and interconnecting angular wall terminate in common planes to join with top and bottom walls 18 and 19, respectively. Within the box-like structure thus formed the interconnecting angular wall 15 forms a seat against which may be rested two of the inner faces of one of

25 the legs L.

Contact between the leg and its associated junction fitting is confined to the angular interconnecting wall 15 through which I form a plurality of openings 25 and 26 to facilitate there-through brazing or welding connections 27 with the two proximate faces of the leg. Openings 28 and 29 are also formed through the two wings 16 and 17, respectively. In the region where the opening 28 is formed, the wing 16 is inset there-across, as at 30. Also in the top and bottom walls, I provide holes 31 and 32, respectively, for the reception of fastening elements (not shown) whereby to secure the seat or top 12 in place.

A front leg and rear leg, to each of which is attached a junction fitting of the kind described,

may be interconnected by a channel rail R having a web 35 with top and bottom flanges 36 spaced apart sufficiently to receive therebetween the top and bottom walls of the junction fitting. When so disposed, the web lies in contact with the wing 17 (see Fig. 4), permitting a brazing connection 37 to be formed through the opening 29 with the web 35. The opposite end of the connecting rail is similarly joined to the junction box which is affixed to the second leg in the same unit. In this way two adjacent legs are firmly and rigidly interconnected by the rail R joined at opposite ends to junction fittings, one of which is affixed immovably to each of the two legs. In addition spot welds 38 may be employed to further interconnect the top and bottom of each junction fitting with the adjacent flanges 36 of the connecting rail.

With two legs thus interconnected as a unit, the furniture article may be shipped or stored in a knock-down condition. For a chair two such units would be provided, also a back and seat together with the necessary parts for final assembly as will now be explained.

Interconnecting bars B are provided for joining together the two units at both front and rear. Each of these bars may be of channel form, one to extend between a pair of chair front legs and another between a pair of chair rear legs, for attachment to the junction fittings which are affixed thereto. For this purpose, I prefer to use stud bolts 40 (see Fig. 4) each having a flat head 41 which may be spot welded at 42 to the web 43 of the connecting bar B. The position of the stud bolt is such that it may be entered through the opening 28 when the end of the connecting bar is brought home against the leg. When so disposed the head 41 will lie within the space afforded by the inset 39, permitting the wing 16 at points above and below the inset to engage with the web of the bar. A spring washer 44 which is fitted around the stud bolt to bear against the inner face of the wing 16 is adapted to receive pressure from a nut 45 when threaded and tightened upon the bolt. In this way each end of the connecting bar B may be secured to the junction box whereby to interconnect the two units for final assembly.

According to Figs. 7 and 8, insetting of the junction fitting wing 16 may be omitted in which case I prefer to fit in the bar channel a reinforcing plate 47 provided therethrough with a hole having an adjacent recess formed by a flared out edge 48. Through this hole a stud bolt 40 may be inserted with its flat head 41 countersunk within the recess, thereby permitting the plate to lie flat at all points against the bar web 49. The bar may be securely affixed, as by welds 50, to the reinforcing plate, and the latter, as by welds 51, to the bar web. A bar having two bolts so secured in place may be easily and quickly attached to the junction fittings of two units that are to be joined, thereby completing the assembly of the furniture article in preparation for its use.

The fitting which may be referred to as a junction box is applicable alike to any of the four legs of a furniture article, being reversed in its position when attached to two of them. Its top and bottom walls in conjunction with the wings and angular interconnecting wall define a structure which is receivable within one end of a channel rail which is adapted to be accurately positioned thereto by a brazing connection with the rail web thereupon and be permanently and rigidly joined

and welding connections with its flanges. This same fitting, because of its angular interconnecting wall which is apertured, forms a seat against which may be rested an extended portion of adjacent faces of the leg which brazing connections may be made at several points. This fitting lies wholly to the inside of the rail and also of the bar that is joined thereto and so is wholly concealed from view as the furniture article is ordinarily presented to the eye. The ends of the rails and bar which may abut the legs assist in this concealment and also impart rigidity thereto. The final nut and bolt connections whereby the interconnecting bars are secured in place, are also hidden from the normal view yet are easily accessible for operation with a conventional wrench. Because of the secure mounting of the stud bolts in the connecting bars, and the flat-wise interengagement of these bars with the end walls of the junction boxes over extended surface areas of the latter, and of reinforcement adjacent these bolts, either by insetting of wings or by addition of a plate to provide extra thickness, adequate provision is made to resist bending, distortion or warping when strains and stresses are encountered even in a high degree. The resulting structure is accordingly both satisfactory in appearance and also strong and rigid, whereby to adapt the furniture article for prolonged and severe service.

The rails and bars, as shown, are identical except as to length, this being an optional matter. For convenience in differentiation I have referred to one as a rail and the other as a bar, but without any intention otherwise to distinguish between them.

I claim:

1. In a furniture article, four legs angular in cross section and each leg having two inner adjacent faces arranged in substantially right angular relation to each other, four junction fittings permanently secured to said legs, each fitting comprising a centrally arranged angular wall forming a seat for said legs and presenting surfaces arranged in substantially right angular relation to each other and of a size to extend substantially across the major portion of said inner furniture leg surfaces and fitting directly against the same throughout the entire area of said angular wall, a pair of wings extending outwardly from opposite ends of said central angular wall and arranged in substantially right angular relation to each other, and substantially horizontal top and bottom walls connecting the wings and the central angular wall at the upper and lower edges thereof, four junction rails having webs and flanges and extending between the legs and receiving and fitting against the wings and walls of the junction fittings, two of the rails connecting the legs in pairs and permanently secured to the junction fittings, and means for detachably securing the ends of the other two rails to the adjacent junction fittings for detachably connecting the pairs of legs.

2. In a furniture article, four legs angular in cross section and each leg having two inner adjacent faces arranged in substantially right angular relation to each other, four junction fittings permanently secured to said legs, each fitting comprising a centrally arranged angular wall forming a seat for said legs and presenting surfaces arranged in substantially right angular relation to each other and of a size to extend substantially across the major portion of said inner furniture leg surfaces and fitting directly

against the same throughout the entire area of said angular wall, a pair of wings extending outwardly from opposite ends of said central angular wall and arranged in substantially right angular relation to each other, and substantially horizontal top and bottom walls connecting the wings and the central angular wall at the upper and lower edges thereof, four rails having webs and flanges and extending between the legs and receiving and fitting against the wings and walls of the junction fittings, two of the rails connecting the legs in pairs and permanently secured to the junction fittings, stud bolts fixed to the other two rails and extending through the wings of the adjacent junction fittings, and nuts arranged on said stud bolts and engaging the contiguous wings of the adjacent junction fit-

tings for detachably securing the ends of said other two rails to the same.

CLARENCE L. DEWEY.
